United States Patent Office

Des. 223,109

Patented Mar. 14, 1972

223,109

ELECTRONIC TERMINAL

James V. Murphy, Warwick, R.I., assignor to Electronic Molding Corporation, Woonsocket, R.I.

Filed Dec. 18, 1970, Ser. No. 26,568

Term of patent 14 years

Int. Cl. D13—03

U.S. Cl. D26—1

FIG. 1

FIG. 2

FIG. 3

FIG. 1 is a side elevational view of an electronic terminal showing my new design, it being understood that the terminal has the same appearance from all sides;

FIG. 2 is a top plan view thereof; and

FIG. 3 is a bottom plan view thereof.

I claim:

The ornamental design for an electronic terminal, substantially as shown and described.
